Thomas M. Chance

UNITED STATES PATENT OFFICE.

THOMAS M. CHANCE, OF PHILADELPHIA, PENNSYLVANIA.

METHOD AND APPARATUS FOR AGITATING FLUID-SEPARATING MEDIUMS.

Application filed May 17, 1923. Serial No. 639,529.

My invention relates to the operation of methods for separating materials of different specific gravities by means of fluid separating mediums of relatively high specific gravity, similar to those described in United States Patent No. 1,224,138, issued to me May 1, 1917, in which an agitated mixture of liquid, (such as water,) and comminuted insoluble solid matter, (such as artificial or natural sands,) is used as a fluid medium or "fluid mass" of relatively high specific gravity, to effect such separation by flotation of the lighter and sinking of the heavier of said materials. The methods in present use for the agitation of such fluid mediums comprise agitation by a rising current of liquid, such as water, (generally designated as hydraulic agitation) agitation by some type of agitating element, such as revolving stirring arms, vertically reciprocated elements, propeller blades and the like and agitation by a combination of hydraulic and mechanical agitation. When hydraulic agitation is used, unless the hydraulic liquid is introduced at a sufficient number of points widely enough separated to secure diffusion and mixing of the hydraulic liquid with the fluid mass, it is often desirable, in order to secure such diffusion and mixing, to introduce some auxiliary mixing or agitating means so that the upwardly rising hydraulic liquid, by the time it has reached the upper portion of the said fluid medium, is sufficiently diffused to produce approximately uniform conditions in the upper part or zone in which separation of the materials to be separated is effected.

When the receptacle in which such separation is effected is made in the form of an inverted cone or pyramid, which types are found convenient for use when it is desired to remove the heavier of the separated materials through a centrally located discharge in the bottom of the receptacle, and when it is found desirable or advantageous to introduce the liquid for hydraulic agitation at or near the base of such inverted cone or pyramid, unless sufficient means are provided for the diffusion of the upwardly rising liquid so admitted throughout the said receptacle, the upwardly rising current of

such liquid will tend to have a greater upward velocity in the central than in the marginal portions of the said receptacle.

The object of my invention is to provide an improved method and apparatus for the diffusion of said hydraulic liquid in such manner as to secure approximately uniform distribution of the upwardly rising hydraulic liquid throughout the upper portion of the receptacle and especially in the region or zone at which separation of the materials to be separated is effected. In my present invention the liquid is diffused through the fluid mass by causing it in whole or in part to pass upwardly through a restricted annular channel or channels between a deflecting element or elements centrally located, and the side of the receptacle. This annular channel or channels may extend continuously around the circumference of said deflecting element or may be subdivided into a plurality of ports or openings.

Such deflecting centrally located element may be made of any desired form or shape, sufficient clearance between it and the sides of the receptacle being provided for the upward flow of the hydraulic liquid, and the downward passage of the heavier separated materials which are to pass into and be withdrawn from the lower portion of the receptacle. It may be made in the form of a disc, cone, cylinder or combination of any of such shapes. While in some cases satisfactory diffusion may thus be obtained without mechanical agitation, it is generally desirable to provide for the rotation of the deflecting element in order to secure uniformity in the distribution and diffusion of the hydraulic liquid, so that this liquid will flow upwardly through all parts of the said annular channel, and not tend to short circuit through a portion of said annular channel.

In my present invention I therefore provide for rotation of the said diffusion element although if desired the apparatus can be operated without rotating the said element.

The drawings Figs. I and II are central vertical cross-sections and views of apparatus by which my invention may be carried out, Fig. I showing in cross-section a deflect-

ing element in the form of a disc and Fig. II showing view of a deflecting element in the form of two truncated opposed cones surmounted by a cylindrical extension. It will be evident that the truncated cones are merely additions to a deflecting element like that shown by Fig. I and that the centrally mounted cylinder confines the fluid mass used for separation to an annular channel between said cylinder and the periphery of the receptacle.

In the drawings 1 is a receptacle of any suitable shape, shown diagrammatically as an inverted cone, and adapted to hold a fluid mass 2 used as a separating medium for the separation of materials of different specific gravities, liquid for agitating said fluid mass being introduced under pressure in the lower part of receptacle 1, through the pipe 3, connected to any suitable source of supply of liquid under pressure, and rising through the fluid mass 2, is diffused through the body of said fluid mass by the revolving deflecting or diffusion element 4 of Fig. I and 4', of Fig. II, which causes the upward rising liquid to pass through the annular channel. The stirring arms 5 also act as mixers or diffusers to diffuse the liquid throughout the fluid mass 2, and also act as ploughs or scrapers to prevent the solid constituent of the fluid mass 2 from settling and accumulating upon the conical sides of the receptacle 1.

Figs. I and II both show a narrow annular channel or space between the periphery of the deflector 4, and the periphery at the point of greatest diameter of deflector 4', and the side of the cone, of about equal width in the two drawings thus forcing the upwardly rising liquid to flow upwardly through this constriction.

Both drawings show two sets of stirring arms below this constriction and but one set above it. As a result of this construction the smaller volume of sand and water below the annular constriction acted upon by two sets of revolving stirring arms will have a higher speed of rotation than the much larger volume of sand and water above said constriction which is acted upon by but one set of stirring arms, thus producing a differential movement of translation between the mass above the said constriction and that below it, and causing the distribution beneath all of the upper portion, of any unequal agitation, local boiling or eddy currents which may be produced or exist in the lower portion, and insuring equal and uniform, (an approximately quiescent,) condition at the top of the fluid mass, such uniformity of conditions being essential to the efficient use of the fluid mass as a "float and sink" medium.

It will also be seen that the upper cylindrical extension of the diffuser 4' of Fig.

II occupies but a relatively small portion, about one-sixth ($\frac{1}{6}$), of the total area of the top of the receptacle, leaving five-sixths ($\frac{5}{6}$) of the area as an annular separating channel along which the floating material is conveyed, by the slow rotation of the fluid mass, from the feed chute 8 to the overflow 12.

It will further be evident that a flat deflector of the type 4 shown by Fig. I will, e. g. in the separation of coal from slate, soon become loaded with a mass of slate, conical in shape, which will perform functions similar to those performed by the upper conical portion of the deflector 4', so that the two types of deflectors 4 and 4' will function in a somewhat similar manner. It is also evident that slate fed in by the feed chute 8 will not be uniformly distributed around the periphery in the lower part of the cone. Such irregular distribution will cause some lack of uniformity in the velocity of the water rising through different parts of the annular constriction, and may be productive of more or less local boiling and eddy currents, the effect of which will however be distributed beneath all of the upper part of the fluid mass by the differences in the speed of rotation between the lower and upper portions of the fluid mass.

The disc deflector 4 is shown with perforations 6 to permit of the upward passage of a portion of the upwardly rising liquid, but such perforations are not essential to the successful operation of my invention, such discs being made perforate or solid as may be desired or with a plurality of ports 6 located near enough to the periphery of the deflector 4 to permit most of the liquid to pass through them thus reducing the quantity passing through the annular channel. It will also be understood that the disc while preferably circular is not necessarily of circular form. The deflector 4' shown by Fig. II may be constructed of any suitable material and may be hollow or solid as may be desired, and with or without ports such as are illustrated in Fig. I by the perforations 6.

In the drawings the fluid mass 2 is designated by horizontal broken lines and strippling, and liquid overlying the fluid mass is designated by horizontal broken lines. In the drawings a feed chute for introducing materials to be separated is shown by 8.

The drawings also illustrate means for rotating the deflector shown by the shaft 9 and bevel gears 10 and 11, although as already stated rotation of such deflectors in many cases may not be necessary to proper functioning of the invention. The outlet or overflow of the apparatus is shown by the overflow trough or chute 12.

The diffusion of liquid effected by a re-

volving diffusion element of the described type is accomplished not only by causing the liquid to pass through the restricted aperture or apertures between the periphery 6 of the diffusion element 4, 4' and the sides of the receptacle 1, but is assisted in greater or lesser degree by the centrifugal force developed in the fluid mass by rotation, and especially in that portion of the fluid mass 10 which lies in juxtaposition to, or in contact with, the diffusion element. The centrifugal force and the agitation and diffusion effected thereby may of course be regulated and adjusted to prevent disturbance of the upper 15 part of the fluid mass by controlling the speed of rotation.

The method and apparatus are not restricted to use in receptacles or containers of the inverted cone type but can be usefully 20 applied to the agitation of fluid masses of the described type in receptacles or containers of cylindrical, polygonal or other suitable shape.

Applicant has constructed diffusing elements of many different shapes and types, 25 the diffusing element may, in fact, be made of almost any shape, provided it is so designed as to obstruct the upward central flow of liquid and force it to pass upwardly 30 through a restricted area or areas between the diffusion element and the side or sides of the containing receptacle and it will therefore be understood that the diffusing elements 4 and 4' are intended diagrammatically 35 to represent diffusing elements of any suitable shape, and further that such elements may be used in combination with stirring arms of any suitable shape or size as illustrated diagrammatically by 5, 5, 5 40 in the drawings, or without any such auxiliary diffusing or agitating arms or equivalent structures.

It will be understood that apparatus for 45 using the method herein described will be provided with the adjunctive devices necessary for the introduction of the materials to be separated and for their separate removal from the apparatus after separation is effected, such as are illustrated by the 50 drawings of the said Patent No. 1,224,138 or are in common use in jigs, classifiers and other devices used for separating materials of different specific gravities.

In both drawings the upper part of the 55 fluid medium which is used as the separating medium is shown as an annular body of such medium occupying the region between the shaft 9, or an upward cylindrical extension of the deflector 4', and the inner 60 periphery of receptacle 1, and the deflectors 4, 4' as shown and described distribute the rising agitating liquid and cause its discharge upwardly through a restricted annular channel, or through apertures annularly located, at a position or positions 65

vertically below the annularly central region of said annular body of separating fluid medium. This delivery of the agitating fluid is of the essence of my invention, because such delivery causes said agitating fluid, in rising and in diffusing upwardly, to diffuse both inwardly and outwardly, towards both the inner and outward periphery of said body of separating fluid medium; if such agitating fluid be delivered to any other portion of the said separating fluid body the liquid will tend to short circuit upwardly near the inner or the outward periphery of said body and equal or uniform agitation thereof cannot be secured.

Having described my invention, I claim—

1. A method for agitating fluid masses composed of liquid and comminuted solids heavier than said liquid and substantially insoluble therein, which consists in introducing a rising column of liquid under pressure below the central portion of said fluid mass, in controlling the quantity of said rising column to prevent bodily upward movement of said fluid mass, in deflecting and restricting the upward flow of said liquid to a region vertically below, and at a substantial distance from, the annularly central part of the top of said fluid mass and in discharging said liquid upwardly from said region into the fluid mass overlying said region; thus distributing said liquid uniformly below said annularly central portion, whereby said liquid in its upward travel will diffuse both inwardly and outwardly from said annular center producing approximately equal upward velocities of said rising liquid throughout substantially the whole superficial area of said fluid mass at and adjacent to its top.

2. A method for agitating fluid masses composed of liquid and comminuted solids heavier than said liquid and substantially insoluble therein, which consists in introducing liquid under pressure vertically below and at a substantial depth beneath a region comprising the annularly central part of the top of said fluid mass, said depth being not less than one-half the annular width of said fluid mass at the top thereof, whereby liquid so admitted in its upward movement will diffuse throughout said fluid mass reaching that portion of fluid mass at the top thereof at greatly reduced velocity, and in controlling the quantity of said liquid introduced at said locus of introduction, whereby the upper portion of said fluid mass, adjacent to the top thereof is continuously and uniformly supplied with rising liquid, but without producing upward movement of said fluid mass, thus uniformly agitating said upper portion of said fluid mass and creating, maintaining and controlling the specific gravity of said upper portion of

said fluid mass substantially constant and uniform throughout the superficial area thereof.

3. Apparatus for the hydraulic agitation of fluid masses composed of liquid and comminuted solids heavier than said liquid and substantially insoluble therein, comprising in combination, a receptacle adapted to contain a fluid mass of the described character; 10 a fluid mass of the described character contained therein; means for introducing liquid under pressure into the lower part of said receptacle, means for controlling the quantity of liquid so introduced and means 15 for deflecting and restricting the upward flow of said liquid to a region vertically below and a substantial distance beneath the annularly central interior of the upper part of said receptacle not occupied by other structures, said means comprising a deflector located in the lower part of said receptacle and adapted to so deflect and so restrict said upward flow, while permitting the discharge of said liquid upwardly from said 20 region, whereby the rising liquid is distributed centrally below said annular central

interior and diffusing in its upward travel effects uniform agitation of fluid mass occupying the upper part of said receptacle but without producing upward movement 30 of said fluid mass.

4. Apparatus for the hydraulic agitation of fluid masses composed of liquid and comminuted solids heavier than said liquid and substantially insoluble therein, comprising 35 in combination, a receptacle adapted to contain a fluid mass of the described character; a fluid mass of the described character contained therein; means for introducing liquid under pressure vertically below and at a 40 depth beneath a region comprising the annularly central part of the operative top of said receptacle not less than one-half the annular width of the operative top of said receptacle and means for controlling the quantity of liquid so introduced at said locus of introduction.

In witness whereof, I have hereunto set my hand at Philadelphia, Pennsylvania, this 14th day of May, 1923.

THOMAS M. CHANCE.
